ADOLPH BRASE AND LEMUEL SALLADEY, OF SCIOTOVILLE, OHIO.

Letters Patent No. 103,134, dated May 17, 1870.

REVOLVING GRATE FOR FIRE-PLACES.

The Schedule referred to in these Letters Patent and making part of the same.

To all whom it may concern:

Be it known that we, ADOLPH BRASE and LEMUEL SALLADEY, of Sciotosville, in the county of Scioto and State of Ohio, have invented a new and useful Improvement in Revolving Grate; and we do hereby declare that the following is a full, clear, and exact description thereof, which will enable others skilled in the art to make and use the same, reference being had to the accompanying drawing forming part of this specification.

Figure 1 is a top view of our improved revolving grate.

Figure 2 is a front view of the same.

Figure 3 is a vertical cross-section of the same, taken in the line x x , fig. 2.

Figure 4 is a detail sectional view of a modified form of the same.

Similar letters of reference indicate corresponding parts.

Our invention has for its object to furnish an improved fire-place grate, which shall be so constructed that it may be revolved or turned into the chimney or into the next room, and which shall have a fire-board formed upon its rear side or end, which may be turned out when no fire is required without removing the grate; and

It consists in the revolving grate, whether made single or double, and having a surface formed upon its rear side or ends, to serve as a fire-board, as hereinafter more fully described.

Are the grates, which are made in the ordinary manner, and which are hung in a frame-work or casing, B, in the same manner as ordinary grates are hung in a fire-place.

The frame-work or casing B is securely attached to a vertical shaft, C, the lower end of which revolves in a step, D, formed in or attached to the lower part of the fire-place, or attached to a bar or frame-work placed in the lower part of said fire-place.

The upper end of the shaft C revolves in bearings in a bar or frame-work, E, placed in the upper part of the fire-place.

When a fire-place is in a partition-wall of a house, the frame or casing B is made with a grate upon the opposite sides, as shown in figs. 1 and 3, so that a fire may be made in each grate at the same time, or a fire

may be made in one grate, and, after one room has been heated, it may be revolved into the other room to heat it. This construction also enables a fire to be made in the grate and revolved into the room to be heated, or the grate may be revolved to enable a fire to be replenished without its being necessary for the attendant to enter the room or disturb those who may be in said room.

In the case of a fire-place in the side-wall of a house, the revolving grate A, B may be made with a single grate, as shown in fig. 4.

The end parts of the frame or casing B, in the case of a double grate, and the rear side of said casing in the case of a single grate, are so formed that, when the double grate is turned one-quarter around, and the single grate one-half around, the end or side thus exposed will serve as a fire-board or summer-piece, thus keeping the grate ready for a fire when required upon chilly or damp days.

By this construction, when the fire is first made, the grate may be turned inward until it has become fully kindled to prevent the sparks from flying out, and thus avoiding the necessity and expense of fire-screens or fenders.

By this construction, also, when it is necessary to leave children alone in the room, the grate may be turned inward and locked, so that it will be impossible for them to set themselves on fire, and, at the same time, heat will be radiated into the room from the end or rear side of the grate.

The grates are provided with ash-pans, F, in the ordinary manner.

Having thus described our invention,

We claim as new and desire to secure by Letters Patent—

An improved revolving grate, A, B, whether made single or double, provided upon its rear side or ends with a surface adapted to serve as a fire-board, substantially as herein shown and described, and for the purposes set forth.

ADOLPH BRASE.
LEMUEL SALLADEY.
